UNITED STATES PATENT OFFICE.

MICHAEL B. DYOTT AND CHARLES G. DYOTT, OF PHILADELPHIA, PA.

LAMP.

SPECIFICATION forming part of Letters Patent No. 334,698, dated January 19, 1886.

Application filed August 14, 1884. Serial No. 140,541. (No model.)

To all whom it may concern:

Be it known that we, MICHAEL B. DYOTT and CHARLES G. DYOTT, citizens of the United States, residing in Philadelphia, Pennsylvania, have invented certain Improvements in Lamps, of which the following is a specification.

Our improvements consist of certain devices for operating the wick - raiser and spreader - button of the lamp, the character of said devices being too fully set forth hereinafter to need preliminary explanation.

In the accompanying drawings, Figure 1 is a sectional view of a lamp with our improvements; Fig. 2, a side view of the device for raising and lowering the wick - holder and spreader-button, and Fig. 3 a sectional plan on the line 1 2, Fig. 1.

A is the reservoir of the lamp, and B the burner-tube, isolated from the reservoir by the intervening annular chamber *a*, but communicating with said reservoir near the lower end through the short supply-tubes *a'*.

F is the wick-carrier, having a rod, *b*, which is contained in a chamber, *c*, Fig. 3, formed on the outside of the burner-tube, the upper end of the rod being bent for adaptation to a cam-slot, *b'*, in a cylinder, *G*, guided on a tubular projection, *d*, of the reservoir, and secured to or forming part of the perforated lower portion, *f*, of the chimney-holder *H*, which is free to turn on said tubular projection of the reservoir, and has a dome or deflector, *g*, and retaining-fingers *h*. The cylinder *G* has another cam slot, *m'*, to which is adapted the upper end of a rod, *m*, said rod passing down through the space *a*, and being bent at the lower end for attachment to the lower end of the tubular-stem *l* of the spreader - button *J*, which occupies a position above the top of the burner-tube, the stem *l* being guided in bearings within the burner-tube. One of the cams occupies a circumferential position farther from the rod engaging it than the other from its rod, whereby during the lowering of the wick-carrier the spreader-button will occupy

a fixed position above the burner - tube; but after the wick has been lowered to the full extent the said button will also be lowered so as to close the upper end of the burner-tube, and thus insure the extinguishing of any gas generated after the lowering of the wick, the button being first raised to its proper position before the wick is raised in order to again light the lamp. Surrounding the outer wall 55 of the burner - tube at the upper end of the same is an annular casting, *K*, which serves to collect and return to the tube through openings *y* any oil which may drip over the top of said tube on the outside of the same. 60

We claim as our invention—

1. The combination of the burner-tube, the wick-raiser, the spreader-button, and a cam-cylinder and operating - rods, whereby said wick-raiser and spreader-button are actuated, 65 all substantially as specified.

2. The combination of the burner-tube, the wick raiser, the spreader - button, operating- rods for said wick-raiser and spreader-button, and a cam-cylinder having two cams, one of 70 which occupies a circumferential position farther from the rod engaging it than the other from its rod, all substantially as specified.

3. The combination of the burner-tube, the chimney-holder, a cam-cylinder forming part 75 thereof, and a wick raiser and spreader-button having projecting rods acted upon by the cam-cylinder, all substantially as specified.

4. The combination of the lamp-reservoir, the burner-tube, the annular space *a* between 80 the two, the cam-cylinder, the wick-raiser, the spreader-button, and an operating-rod for the latter, passing through the space *a*, as set forth.

In testimony whereof we have signed our names to this specification in the presence of 8: two subscribing witnesses.

MICHAEL B. DYOTT.
CHARLES G. DYOTT.

Witnesses:

JOHN M. CLAYTON,
HARRY SMITH.
